UNITED STATES PATENT OFFICE.

EZEKIEL VAN NOORDEN, OF BOSTON, MASSACHUSETTS.

CONDUCTOR-PIPE.

SPECIFICATION forming part of Letters Patent No. 253,564, dated February 14, 1882.

Application filed October 14, 1881. (No model.)

To all whom it may concern:

Be it known that I, EZEKIEL VAN NOORDEN, of Boston, in the county of Suffolk and State of Massachusetts, have invented a new and useful Improvement in Conductor-Pipes, of which the following is a specification.

This improvement relates to the metallic pipes used for conducting the water from the gutters and roofs of buildings; and it has for its object the strengthening of such pipes in such a manner that the action of the ice and frost cannot injure or burst them.

In the accompanying drawings, in which similar letters of reference indicate like parts, Figure 1 is a view of a portion of a conductor-pipe with its sections separated. Fig. 2 is a view of the same with its sections united.

A A' represent two sections of pipe constructed in the usual manner.

B is a piece of metal wire wound spirally round the pipe, as shown, and terminating at each end in a hook, B', formed by bending the wire back upon itself. The wire is secured to the pipe near its ends by staples C, which are driven into the pipe and clinched on the inside. This wire is wound upon and secured to the pipe while it is in sections, one wire for each section, as in Fig. 1. When the sections are united to form the conductor the wires upon said sections are secured together by slipping a loop of wire, D, over the hooks B' next each other, thus securing the wires together and making them practically one wire. These loops D may be of any convenient shape, the one shown being perhaps the simplest, it being formed by passing a short piece of wire through the two hooks B', and twisting the ends together. The hooks are left conveniently open in order that they may be readily tied together. The wire may be fastened to the pipe in any practicable manner, the staples C being probably the most convenient.

Each section of pipe is constructed with an

expansion-joint, E, which allows of a very slight expansion until checked by the wire 45 above described.

I am aware that in the construction of elastic or pliable hose-pipes or tubes wire has been externally wound thereupon. In one instance a rubber or elastic pipe for such purposes has 50 been wound with wire next the end into which the water flows, thereby imparting rigidity and stiffness at that point. In another instance leather-tinned wire coils, and another external substance covering the wire have been employed in the construction of an elastic or pliable pipe. My device differs from these in object and construction, being a stiff metallic pipe for conducting water from roofs, made in sections, each of which is spirally wound with 55 wire in such a manner that the coils are at considerable distances apart, each section being complete in itself. The object is solely to prevent the bursting of the pipe from the action of the frost. 65

Having thus fully described my invention, what I claim, and desire to secure by Letters Patent, is—

1. A water-conductor pipe, made in sections, each section provided with an expansion-joint 70 and externally wound with wire, substantially as and for the purpose set forth.

2. In combination with the pipe A, the wire B, wound spirally around it and provided with the hooked ends B', said wire being fastened 75 immovably to the pipe, substantially as and for the purpose described.

3. In combination with the sections A A' of pipe, the wire B, provided with the hooked ends B', the adjacent ends of two wires being 80 connected by the wire loop D, substantially as and for the purpose specified.

EZEKIEL VAN NOORDEN.
